ASPIRATOR FOR ADMINISTERING
MEDICINE

John H. Emerson, Cambridge, Mass.

Application August 1, 1946, Serial No. 687,586

10 Claims. (Cl. 123—195)

1
This invention pertains to aspirators such as are employed in administering medical substances in spray form, for instance for inhalation by a patient, and in particular to an aspirator designed for use with medicaments which are too expensive to waste. For example penicillin has been found effective as an inhalant in the treatment of some forms of asthma, but at the present price of penicillin it is not available to many persons who would benefit from its use because of the wasteful methods of administration.

It has heretofore been proposed to employ apparatus for this purpose wherein the penicillin or other medical substance is atomized by a jet of oxygen and wherein the patient by the operation of a valve or vent limits the actual atomization to the period of inhalation so that the medicine is not wasted during exhalation. While this prior apparatus is useful, it is necessary for the patient to manipulate the control valve or vent. This places a considerable burden upon a patient even though he may be able to do so, and many patients are wholly unable to perform this operation.

The object of the present invention is to provide apparatus of the type above referred to wherein a liquid medicament is atomized by a jet of compressed gas, for example oxygen, and having provision for the automatic limitation of the atomizing action to the period of inhalation, thus relieving the patient of the necessity of manipulating any control devices, and at the same time avoiding any waste of the expensive medicine. Another object of the invention is to provide simple atomizing apparatus for the intended purpose and such as may be manufactured at a reasonable cost so as to make it generally available. Other and further objects and advantages of the invention will be pointed out in the following more detailed description and by reference to the accompanying drawings wherein.

Fig. 1 is a diagrammatic elevation illustrating the novel apparatus;

Fig. 2 is an edge elevation, partly broken away and to larger scale, showing details of the control mechanism with the parts in the position which they occupy during inhalation; and

Fig. 3 is a view similar to Fig. 2 but showing the position of the parts during exhalation.

Referring to the drawings, the numeral 1 designates a casing of any suitable material, for instance a moulded plastic, glass or metal, defining a chamber 2, the lower part of which, in

2
the simple construction herein illustrated, constitutes a reservoir for a body 3 of the medicinal substance which is to be administered. The casing 1 is provided with a tubular branch 4 defining the delivery passage 5. This branch 4 may be shaped to be held in the mouth of the patient or alternatively it may be shaped to fit into one nostril or into both nostrils. The casing also has the tubular branch 6 providing the breathing port 7, this port being of a size sufficient to admit the passage of air in sufficient quantity for breathing.

Within the chamber 2 there is arranged a jet nozzle 8 which is supplied with the medicinal substance from the body 3 by means of an elevating tube 9 supported by a rigid bracket 10. The upper end of the elevating tube is so arranged, relatively to the jet nozzle 8, that the aspirating effect of gas delivered from the jet nozzle lifts the medicinal substance to the nozzle tip so that the medicinal substance is atomized by the jet of gas issuing from the nozzle. The nozzle is supplied with gas, by means of a flexible tube 11 and connections, to be described, 25 from a tank 12, for example a commercial oxygen tank, provided with the usual gauge 13 and control valve, and the delivery tube 14.

This tube 14 communicates with a rigid tubular support 15 to whose lower end the flexible tube 11 is connected. This support 15 carries a pressure motor 16 comprising a case 17 which houses a very light and flexible diaphragm 18. The case defines a chamber 19, at one side of the diaphragm, which communicates by means of a tube 20 with the chamber 2 of the casing 1. Since the chamber 19 of the pressure motor communicates with the chamber 2 of the casing 1, the diaphragm is responsive to pressure variations in the chamber 2. The right-hand side of the diaphragm is open to atmospheric pressure at all times.

The support 15 is provided with a discharge port 21 which is controlled by a movable valve head 22. As illustrated, this valve head is carried by a lever 23 having an arm 23^a which engages the central part of the diaphragm 18 so that motion of the diaphragm causes the valve 22 to be seated or unseated.

Assuming that gas under pressure is being supplied through the tube 14 to the tubular support 15 and is thus available for delivery to the jet nozzle 8, if the patient places the part 4 in his mouth and inhales, the pressure in chamber 2 is slightly reduced, and this reduction in pressure is communicated to the chamber 19, thus

causing the diaphragm 18 to move to the left as shown in Fig. 2. This closes the valve 22, so that the gas under pressure flows through the conduit 11 to the nozzle 8 and aspirates and atomizes the medicinal substance. The patient thus inhales the atomized material. As soon as the patient begins to exhale, the pressure in the chamber 2 rises very slightly above atmospheric pressure, thus moving the diaphragm 18 to the right, as shown in Fig. 3. This movement of the diaphragm to the right unseats the valve head 22. Since the discharge port 21 in the conduit leading from the gas supply to the nozzle is of substantially greater area than the area of the tip of the nozzle 8, the gas now freely discharges through the port 21 and the atomizing action in the casing ceases. Thus no more of the medicinal substance is lifted by the tube 3 and there is no waste of this material during exhalation. As soon as the patient begins to inhale again, the diaphragm 18 moves to the left, the valve 22 closes and the cycle is repeated.

Thus the atomizing of the medicinal material takes place only during those periods in which the patient is inhaling and while the atomized material is useful. During exhalation the medicinal substance is not atomized. The operation is wholly automatic and requires no thought or effort on the part of the patient.

While one desirable embodiment of the invention has been illustrated by way of example, it is to be understood that the invention is broadly inclusive of any and all modifications falling within the scope of the appended claims.

I claim:

1. Atomizing apparatus for administering a medicinal substance and wherein a jet nozzle is so arranged as to discharge the atomized medicinal substance into a chamber and wherein the chamber communicates with a delivery passage and has a constantly open breathing port in its wall, and having provision for supplying gas under pressure to the jet nozzle, characterized in having a valve operative to determine whether the gas shall be delivered to the jet nozzle or vented to the atmosphere, and automatic means responsive to the pressure in said chamber for actuating the valve.

2. Atomizing apparatus for administering a medicinal substance and wherein a jet nozzle is so arranged as to discharge the atomized medicinal substance into a chamber and wherein the chamber communicates with a delivery passage and has a constantly open breathing port in its wall, and having provision for supplying gas under pressure to the jet nozzle, characterized in having means including a constantly open unobstructed conduit for supplying pressure gas to the jet nozzle, said conduit having a discharge port intermediate the jet nozzle and the gas supply, valve means for closing said discharge port, and means responsive to the pressure in the chamber for actuating the valve.

3. Atomizing apparatus for administering a medicinal substance and wherein a jet nozzle is so arranged as to discharge the atomized medicinal substance into a chamber and wherein the chamber communicates with a delivery passage and has an open breathing port in its wall, and having provision for supplying gas under pressure to the jet nozzle, characterized in having means including a constantly open unobstructed conduit for supplying gas under pressure to the jet nozzle, said conduit having a discharge port intermediate the nozzle and gas supply, a valve

operative to close said discharge port, and a pressure motor which is responsive to pressure variations in said chamber, the pressure motor being so designed and arranged as to open the valve in response to exhalation pressure in the chamber.

4. Atomizing apparatus for administering a medicinal substance and wherein a jet nozzle is so arranged as to discharge the atomized medicinal substance into a chamber and wherein the chamber communicates with a delivery passage and has an open breathing port in its wall, and having provision for supplying gas under pressure to the jet nozzle, characterized in having means including a constantly open unobstructed conduit for supplying gas under pressure to the jet nozzle, the conduit having a discharge port of a capacity greater than that of the jet nozzle intermediate the nozzle and gas supply, a valve operative to close said discharge port, and a pressure motor which is responsive to pressure variations in said chamber, the pressure motor comprising a diaphragm which moves in one direction or the other, respectively, in response to exhalation and inhalation pressures in said chamber, and means for transmitting motion from the diaphragm to the valve.

5. Atomizing apparatus for administering a medicinal substance and wherein a jet nozzle is so arranged as to discharge the atomized medicinal substance into a chamber and wherein the chamber communicates with a delivery passage and has a constantly open breathing port in its wall, and having provision for supplying gas under pressure to the jet nozzle, and wherein the chamber is shaped to provide a reservoir for the medicinal substance, and houses a device for elevating the medicinal substance in response to the aspirating action of the gas jet delivered from the nozzle, characterized in having valve means and a valve-actuating motor, the latter responsive to the pressure variations in the chamber, for cutting off the delivery of gas by the jet nozzle during periods of exhalation.

6. Apparatus for use in administering a liquid medicament in atomized form for inhalation by a patient, said apparatus comprising a vaporizing nozzle and means including a conduit for supplying gas under pressure to the nozzle, a valve controlling a delivery port intermediate the ends of said conduit, and automatic valve-actuating means responsive to the pressure of the gaseous medium exhaled by the patient operative to vent the supply of gas to the nozzle during periods of exhalation, thereby to terminate vaporization.

7. Apparatus for use in administering a liquid medicament in atomized form for inhalation by a patient, said apparatus comprising a jet nozzle, means to deliver the liquid medicament in aspirating relation to the nozzle, means for supplying gas under pressure to the nozzle and automatic means including a valve which controls a discharge port and a pressure motor for actuating the valve, the motor being responsive to the pressure of the gaseous medium exhaled by the patient thereby to open the discharge port and to divert the supply of gas from the nozzle to the atmosphere, thereby to cease vaporization during periods of exhalation.

8. Apparatus for use in administering a liquid medicament in atomized form for inhalation by a patient, said apparatus comprising means for supplying gas under pressure to a nozzle, a container for liquid medicament, a tube for elevating

the liquid to the nozzle tip in response to the aspirating action of the issuing gas jet, valve means including a movable valve head operative alternatively to deliver gas to the nozzle or to vent the gas to the atmosphere and a pressure motor including a movable diaphragm which moves in one direction in response to exhalation pressure and in the other direction in response to inhalation pressure, and means so connecting the diaphragm and valve head that the valve head is actuated to vent the gas to the atmosphere, thereby to cease vaporization during periods of exhalation.

9. Apparatus for use in administering a medicinal substance in atomized form for inhalation by a patient, said apparatus comprising a vaporizing nozzle, and having provision, including a constantly open, unobstructed conduit for supplying gas under pressure to said nozzle, said conduit having a vent port intermediate its ends, and a movable valve head operative at times to close said port, and automatic means responsive to exhalation pressure to open said valve thereby to vent the gas to the atmosphere at a point intermediate the ends of the conduit.

10. Apparatus for use in administering a medicinal substance in atomized form, comprising means defining a chamber through which the

patient inhales and exhales, the chamber having a constantly open aperture in its wall of a size sufficient to pass air in the amount requisite for breathing, but such that the pressure in the chamber decreases and increases slightly in response to inhalation and exhalation respectively, a nozzle arranged to discharge the atomized medicinal substance into the chamber, a constantly open unobstructed conduit for leading gas under pressure from the source of supply to the nozzle, and means responsive to exhalation pressure within the chamber to vent the gas on its way from the supply to the nozzle to the outer atmosphere.
